BUMPER AND HITCH COMBINATION

Edward Zorn, Encino, and Bert J. Sherwood, Los Angeles, Calif., assignors to Chemplate Corporation, Los Angeles, Calif., a corporation of California

Filed June 2, 1967, Ser. No. 7,346

Term of patent 14 years

(Cl. D14—6)

Fig. 1

Fig. 2

Fig. 3

Fig. 4

Fig. 5

FIGURE 1 is a perspective view of our bumper and hitch combination;

FIGURE 2 is a front elevational view thereof;

FIGURE 3 is a plan view thereof;

FIGURE 4 is an end elevational view thereof; and

FIGURE 5 is a cross-sectional view, in elevation, taken along the line 5—5 of FIGURE 3.

The dominant features of our design reside in the portions shown in full lines.

We claim:

The ornamental design for a bumper and hitch combination, as shown and described.
